UNITED STATES PATENT OFFICE

FRANKLIN S. MORRISON, OF RICHLAND, OREGON.

WATER-POWER DEVICE.

1,127,489.

Specification of Letters Patent. Patented Feb. 9, 1915.

Application filed December 2, 1912. Serial No. 734,585.

To all whom it may concern:

Be it known that I, FRANKLIN S. MORRISON, a citizen of the United States, residing at Richland, in the county of Baker and State of Oregon, have invented new and useful Improvements in Water-Power Devices, of which the following is a specification.

This invention relates to a water power device which is adapted to be mounted within a sluice-way or the like, wherein it is completely submerged within the current of water, the primary object thereof being to provide a device of this character including a pair of spaced shafts having sprocket wheels mounted thereupon, spaced chains mounted upon said wheels, and a plurality of pivoted vanes attached to said chains and adapted to cause operation of the said shafts during longitudinal movement through the sluice-way in one direction, in the "power sweep" only, the said vanes being unaffected by the current during movement in the opposite direction. This construction of the power device and its disposition within the sluice-way being provided so that the water current may act upon the vanes during a considerable length of movement thereof.

A further object of the invention is to provide a device of this character having means for limiting the movement of the pivoted vanes into their operative position.

A still further object is the provision of the flexible bracing members adapted to ease the motion of the vanes as they gravitate downwardly into their operative position when passing into the "power sweep", thus preventing excessive shock upon contact of the vanes with their respective limiting members.

The invention consists in the features of construction, combination, and arrangement of parts hereinafter fully described and claimed, reference being had to the accompanying drawing, in which:

Figure 1 is a side elevation of a power device constructed in accordance with the invention; Fig. 2 is a longitudinal sectional view taken vertically through the same; and, Fig. 3 is a transverse sectional view taken on line 3-3 of Fig. 1.

In the drawing, the numerals 1 and 2 designate the relatively spaced shafts which extend transversely through the side walls of the sluice-way 3. A pair of spaced

sprocket wheels 4 is mounted upon each of the said shafts, one sprocket wheel on each shaft being in alinement with one sprocket wheel upon the other shaft. An endless chain 5 connects the alining sprocket wheels of each pair, and these chains 5 are adapted to be connected at spaced points by a plurality of swinging vanes 6 which are pivoted to the said chains as at 7. Each vane is transversely curved adjacent its pivoted inner edge as at 8 and is again curved, similarly adjacent its outer edge as at 9 so as to form a sort of pocket, which construction prevents the water from readily escaping past the same after its impact therewith. In order to cause the water to impinge even more forcibly against the vanes, each vane is adapted to be maintained in an inclined position, as shown in the drawing, by means of the limiting members 10, which are secured to the links on both chains adjacent the links to which the corresponding vane is pivoted. These limiting members serve effectively to brace the vanes against the force of the current, in addition to maintaining the same in the proper angular relation to the supporting chains. A pair of flexible bracing members 11 is attached to a pair of lugs 12 formed upon the active face of each vane at points spaced from the ends thereof. The other end of each chain 5 is secured to an eye 13 formed upon one of the limiting members 10 which is operatively associated with the next succeeding vane. These chains are adapted to aid in bracing the vanes when in operative position in the power sweep, and are further adapted to ease the gravitational movement of the vanes as they pass downwardly into the power sweep. The chains at this point are passing over the upstream sprocket wheels and thus, the outer faces of the spaced lugs thereupon will be separated by a greater distance than when either in the power sweep or the upper return sweep, which fact will be clearly apparent upon reference to Fig. 1. Thus, each vane will not fall suddenly upon its limiting members as it gravitates into the power sweep, but the strain will come to bear upon its flexible bracing members, this easing its motion and permitting it to strike the limiting members without excessive shock. One of the shafts, which in this instance is shown

to be the shaft 2, is connected in suitable manner with the machinery to be operated by the power device, which in this instance is a belt and pulley transmission.

5 The sprocket wheels 4 are of sufficient diameter to prevent the flexible bracing members from depending low enough to engage with the lowermost vanes or limiting members, when the said chains are passing through the inoperative sweep of the device, the vanes being in collapsed position upon the uppermost stretches of the supporting chains when in this sweep.

As the vanes lie flat against the portions 15 of the supporting chains to which they are attached when in the operative sweep of the device, they occupy a very limited amount of vertical space, thus permitting the top portion of the device to be positioned in 20 close proximity to the top wall of the sluice way. This permits the use of wide vanes the width thereof being entirely dependent upon the space between the lower portion 25 of the device and the bottom portion of the sluice-way.

It is to be understood that this power device is peculiarly adapted for use in a sluice-way of the construction described, but that it may be used in any open stream of water,

such as a river or the like, without departing from the general scope of the invention and the claim appended hereto.

What is claimed is:

A device of the class described comprising a pair of rotary members, power transmission means connected with one of said rotary members, a flexible element extending around the said rotary members, a plurality of longitudinally spaced, transversely extending vanes pivoted to the outer surface of the said element, a solid limiting member provided in connection with each vane for limiting its movement into operative position projecting outward from the element, and a flexible member connecting each vane with the said element at a point disposed at the opposite side of the vane from the first-named limiting member, each flexible member being adapted to be drawn taut when the corresponding vane is in engagement with its respective limiting member.

In testimony whereof I affix my signature in presence of two witnesses.

FRANKLIN S. MORRISON.
